CLAIM

The ornamental design for a head massager with stacked ball handle, as shown and described.

DESCRIPTION

FIG. 1 is a front elevational view of a head massager with stacked ball handle showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The break lines in FIGS. 1-7 are for the purpose of showing indefinite lengths of the rods.
